UNITED STATES PATENT OFFICE.

GEORGE H. SARGENT, OF EVANSTON, ILLINOIS.

SHIFT-RAIL.

No. 910,089.

Specification of Letters Patent.

Patented Jan. 19, 1909.

Application filed June 17, 1908. Serial No. 439,028.

To all whom it may concern:

Be it known that I, GEORGE H. SARGENT, a citizen of the United States, residing at Evanston, in the county of Cook and State 5 of Illinois, have invented certain new and useful Improvements in Shift-Rails, of which the following is a specification.

My invention pertains to shift-rails which are adapted to be used in connection and 10 coöperation with car rerailers or replacers to assist in again placing the wheels of a derailed car or truck on the railroad rails.

Heretofore, it has been customary and usual to employ wooden wedges, planks, 15 &c., on which to roll the derailed wheels to the replacers at or near the railroad rails. Such wedges, planks, &c., are ordinarily destroyed by once using, the flanges of the 20 wheels riding on them usually splitting them, thereby rendering them unfit for further use. If some such supporting means is not employed, then the derailed wheels cut and mar the cross-ties and damage the loose ballast when rolled across the same.

25 The object of my invention is therefore to do away with the necessity of employing wooden wedges, planks and timber, the expense of which is of some moment, and provide shift-rails simple in construction and 30 economical of manufacture to act as supports for the treads of the wheels while they are being rolled to the railroad rails, these shift-rails bridging the spaces between the ties and elevating the wheels so that their 35 flanges do not harm the road-bed, ties or the like.

On the accompanying drawings I have 40 illustrated a preferred and desirable embodiment of my invention, Figure 1 showing in end elevation a pair of my improved shift-rails laid adjacent to the railroad rails and having traveling thereon the treads of a pair of derailed car-wheels; Fig. 2 is a plan view of one of these shift-rails; Fig. 3 is a side elevation of the shift-rail shown 45 in Fig. 2, and illustrates how the same bridges the space between adjacent cross-ties or sleepers; and Fig. 4 is an end elevation of the shift-rail shown in Figs. 2 and 3, 50 and illustrates the manner in which the same carries the wheel on its tread at a sufficient height to raise the flange of the wheel above the base and above the cross-ties.

Each of the shift-rails has a substantially- 55 rectangular base 10 of sufficient length to rest upon the top surfaces of two or more

cross-ties or sleepers, the top face of this base 10 having extended longitudinally and centrally thereof a track section or portion 11, the top surface of which is at a sufficient 60 elevation above the top face of the base so that when the tread of a car-wheel is rolling on the top of the track its flange will escape the base, as is clearly shown in Fig. 4. At one end of the shift-rail the track 11 is extended beyond the end of the base 10 and downwardly to provide the lug, finger or abutment 12 intended to engage the face of the cross-tie, as shown in Fig. 3, to prevent lengthwise displacement of the rail while 65 the derailed wheel is being rolled upon the same. It should also be noticed that each end of the track 11 is rounded or inclined at 13 and 14 to facilitate the rolling of the car-wheel thereupon.

A pair of these shift-rails is laid on the cross-ties or sleepers in front of the treads of the derailed car-wheels and may be pointed or aimed toward the railroad rails, if desired. The derailed car or truck is then 70 pushed or pulled toward the shift-rails, the wheels of which travel up the inclines 13 onto the tracks 11, their flanges being at one side of the tracks, as shown in Figs. 1 and 4. The load of the truck or car is therefore 75 transmitted to the shift-rails through the treads of the wheels, the flanges thereof being prevented by their elevation or height above the bases of the shift-rails and above the cross-ties from in any wise damaging 80 the road-bed. The fingers or abutments 12, as is obvious, prevent lengthwise shifting of 85 these rails while the wheels are being rolled thereupon or thereon. When the derailed car-wheels have sunk to some little depth in 90 the ballast between the cross-ties, it may be desirable or necessary to insert the ends of the shift-rails beneath the treads of the 95 wheels with the shift-rails in an inclined or elevated position, but as soon as the treads 100 of the wheels pass upon the tracks 11 the shift-rails will be brought to the horizontal position indicated in the drawings, bridging the spaces between the cross-ties and 105 properly supporting the wheels so that they may be readily rolled upon suitable replacers or rerailers.

I claim:

A shift-rail having a flat base adapted to 110 rest on any suitable support and having on its top face a narrower track on the top of which the tread of a derailed wheel is adapt-

ed to roll, the top of said track being at a substantially uniform height above the bottom of said base, said track also being of sufficient height to raise the flange of the 5 wheel above the base and cross-ties upon which the rail may be placed, and having one or more of its ends inclined or beveled to facilitate the rolling of the wheel on to the track, said track at one end of the shift-

rail extending below said base and forming 10 an abutment to co-act with the cross-tie to prevent displacement or slipping of the shift-rail, substantially as described.

GEORGE H. SARGENT.
